(57) **CLAIM**

The ornamental design for a contoured display and bezel in combination, as shown and described.

DESCRIPTION

FIG. 1 is a front, top, and right side perspective view of the contoured display and bezel in combination, showing the new design;

FIG. 2 is a front side elevational view thereof;

FIG. 3 is a rear side elevational view thereof;

FIG. 4 is a right side elevational view thereof;

FIG. 5 is a left side elevational view thereof; and,

FIG. 6 is a top plan view thereof; and,

FIG. 7 is a bottom plan view thereof.

The broken lines immediately adjacent to the shaded areas represent the bounds of the claim, and other broken lines represent unclaimed portions of the design. None of the broken lines form a part of the claimed design.
